UNITED STATES PATENT OFFICE.

FRANK E. BOCORSELSKI, OF RICHMOND, VIRGINIA.

METAL-CUTTING TOOL.

1,068,211.

Specification of Letters Patent.

Patented July 22, 1913.

Application filed January 21, 1913. Serial No. 743,236.

To all whom it may concern:

Be it known that I, FRANK E. BOCORSELSKI, of Richmond, in the county of Henrico and State of Virginia, have invented a certain new and useful Improvement in Metal-Cutting Tools, of which improvement the following is a specification.

The object of my invention is to provide a construction whereby the cost of maintenance of high speed taps, reamers, or other peripheral cutting tools may be reduced, and the depth of cut thereof accurately regulated as desired.

The improvement claimed is hereinafter fully set forth.

In the accompanying drawings: Figure 1 is a view, partly in elevation and partly in longitudinal central section, illustrating my invention as applied in connection with a stay bolt tap; Fig. 2, an end view, as seen from the left; and, Figs. 3 and 4, transverse sections, on the lines *a a* and *b b*, respectively, of Fig. 1.

My invention is herein exemplified as applied in connection with a stay bolt reamer, 1, used for cutting internal threads in two firebox sheets, A. and B, of a locomotive boiler, which reamer is provided with a plurality of peripheral screw cutting threads, 1^a, of the usual form. In the practice of my invention, I provide a mandrel, 2, of hardened and ground tool steel, which is provided, at one end, with a squared hub, 2^a, for the application of means by which it may be rotated, and is externally threaded for a portion of its length adjoining said hub. A longitudinal groove, 2^c, is cut in the mandrel, for a purpose hereinafter described, and the mandrel is detachably connected to the reamer by means of a tongue, 2^b, on the mandrel, at the end of its external thread farther from the hub, said tongue engaging a corresponding transverse slot, 1^b, in the adjacent end of the reamer. The relative location of the tongue and slot may, if preferred, be reversed, without involving any difference in principle or operative result. The mandrel extends through the reamer, and an externally threaded stem, 2^d, is formed on its opposite end, which thread engages a corresponding internal thread in the head, 3^a, of a guide or pilot stem, 3, which fits in a hole in the boiler sheet farther from the reamer, in line axially with the latter, and serves to guide it when one or both of two holes in the sheets

is or are to be threaded in line one with the other.

The depth of the cut made by the reamer is regulated, as desired, by an adjusting sleeve, 4, which is internally threaded at and adjoining one of its ends, to engage the external thread of the mandrel, 2, and has, for the remainder of its length, a plain bore, of greater diameter than the reamer, 65 which it surrounds. The end of the adjusting sleeve farther from the mandrel is brought to a thin edge, which bears on the outer side of the boiler sheet in which the reamer operates.

An annular washer plate, 5, having an internal tongue, 5^a, which engages the groove, 2^c, of the mandrel, 2, is fitted thereon, and is clamped to the adjacent end of the adjusting sleeve, 4, by a check nut, 6, which 75 engages the external thread of the mandrel. In the operation of the appliance, the adjusting sleeve is screwed on the mandrel to such position in the length thereof as may be required by the desired depth of cut, and 80 relative movement of the mandrel and adjusting sleeve is prevented by the engagement of the tongue of the washer plate with the groove of the mandrel, when the washer plate is brought to a tight bearing against 85 the adjusting sleeve by screwing up the check nut.

It will be obvious to those familiar with the art of cutting metal, that the wear of the mandrel and adjusting sleeve, both of 90 which are made of hardened and ground steel, is practically negligible, while that of the cutting tool is rapid. The economy of renewal, as compared with ordinary practice, in which the mandrel and tool are integral, is therefore material. It will also be seen that the adjustment to desired depth of cut may be readily and accurately made, and be maintained without liability to accidental displacement.

I claim as my invention and desire to secure by Letters Patent:

1. In combination with a cutting tool, a mandrel having its ends externally threaded and projecting through the cutting tool, 105 means at the inner end of the threads at one end of the mandrel to detachably connect said mandrel to said cutting tool, a stop member threaded onto said last named end of the mandrel, and a pilot stem having one 110 end interiorly threaded and engaged with the other threaded end of the mandrel, said

end of the pilot stem engaging the adjacent end of the cutting tool and holding said connecting means in locked position.

2. In combination with a cutting tool, a mandrel arranged to have its ends project through the tool, a detachable connection between one end of the tool and the mandrel, the mandrel having its end at the opposite end of the tool exteriorly threaded, and a pilot stem threaded over said threaded end of the mandrel and engaging said opposite end of the tool to hold the connection in locked position.

3. A mandrel comprising a central tool-receiving portion, a reduced threaded front end portion, and an enlarged threaded shank end portion, means at the junction of said central and shank end portions to engage the tool and hold it against rotation, a pilot stem adapted to be screwed on said front end against the end of the tool, a gage sleeve adapted to be screwed on said shank end

so as to project forwardly around the tool, and means to clamp said sleeve in adjusted position.

4. A mandrel having a threaded shank end portion of enlarged diameter, a central smooth portion for the reception of a tubular cutting tool, and a threaded front end portion of reduced diameter, a pilot stem adapted to be screwed on to said reduced front end portion and thereby clamp the tool against the shoulder formed at the junction of the shank and central portions, means to prevent the tool from rotating relatively to the mandrel and an adjustable stop sleeve screwed on said shank portion and projecting forwardly over the rear end of the tool-receiving portion.

FRANK E. BOCORSELSKI.
